United States Patent Office

Des. 234,174
Patented Jan. 28, 1975

234,174

TISSUE HOLDER

Raymond U. H. Tegner, Lodi, Wis., assignor to
Amerock Corporation, Rockford, Ill.

Original design application Nov. 10, 1972, Ser. No.
305,567. Divided and this application Oct. 24,
1973, Ser. No. 409,057

Term of patent 14 years

Int. Cl. D6—06

U.S. Cl. D6—97

FIG. 1

FIG. 2

FIG.3

FIG.4

FIG.5

FIG.6

FIG. 1 is a front view of a tissue holder, such as for toilet tissue, showing my new design.

FIG. 2 is a bottom view of the holder.

FIG. 3 is a side view of the holder as seen from the right in FIG. 1.

FIG. 4 is a fragmentary sectional view taken along the line 4-4 in FIG. 1.

FIG. 5 is a fragmentary sectional view taken along the line 5-5 FIG. 1.

FIG. 6 is a fragmentary sectional view taken along the line 6-6 in FIG. 2.

This application is a division of my co-pending application Ser. No. 305,567, filed Nov. 10, 1972.

I claim:

The ornamental design for a tissue holder, as shown.
